UNITED STATES PATENT OFFICE.

ROBERT W. WHITE, OF ELWOOD, INDIANA, ASSIGNOR TO PITTSBURGH PLATE GLASS COMPANY, A CORPORATION OF PENNSYLVANIA.

MOLD FOR CASTING CLAY ARTICLES.

1,415,213.

Specification of Letters Patent.

Patented May 9, 1922.

Application filed August 24, 1920. Serial No. 405,709.

To all whom it may concern:

Be it known that I, ROBERT W. WHITE, a citizen of the United States, and a resident of Elwood, in the county of Madison and 5 State of Indiana, have made a new and useful Invention in Molds for Casting Clay Articles, of which the following is a specification.

The invention relates to molds for use in 10 casting clay articles such as tank blocks, floaters, pots, tuilles and the like. It has for its primary objects, the provision of a mold for the purpose specified which, (1) is cheaper than the plaster molds heretofore used, (2) requires less skill to construct than the plaster molds, (3) permits the reuse of the material employed, and (4) is subject to less breakage than the plaster molds.

When clay is cast in shapes such as those 15 specified, the walls of the molds must be constructed of material adapted to take up the excess moisture in the clay and promote the setting of the clay. Plaster of Paris has been used with some success for this purpose 20 in connection with small articles, but is objectionable for a number of reasons and particularly so in connection with the formation of relatively large articles. One objection is the difficulty involved in utilizing 25 the plaster after the mold is cracked or broken, as the used plaster is almost worthless and forms an accumulation which is often a source of expense to dispose of. Further the making of plaster molds is a 30 trade so that skilled and expensive labor is required. As the size of the mold is increased its weight tends to cause increased breakage in handling as the plaster is relatively fragile and the expense is greatly increased due to the great thickness in the 35 walls required in order to secure the necessary strength. The weight due to the thick walls also makes the labor of handling the mold in assembling and disassembling very 40 heavy.

The present invention is designed to overcome the objectionable features of the plaster mold by substituting a mold having a supporting structure of wood, iron, or other 45 similar relatively strong material with a lining of plaster board or other material having a capacity for absorbing moisture corresponding to that of plaster. Such a mold may be made of ample strength for 50 producing poured or cast articles of the

largest size such as pots or tuilles, and the lining of plaster board can be removed and dried and used over again many times. Molds of this character are not subject to 55 breakage to any extent and may be constructed by relatively unskilled labor. They are also much lighter and more easily handled.

Certain embodiments of the invention are illustrated in the accompanying drawings, 60 wherein:—

Figure 1 is a plan view of a mold constructed in accordance with the invention and designed for casting tank blocks. Fig. 2 is a section through the mold of Fig. 1 on 65 the line II—II, and Fig. 3 is a horizontal section taken through a portion of the wall of a pot mold embodying the invention.

Figs. 1 and 2 illustrate a knock-down mold containing the improved construction and 70 designed for the production of tank blocks. This mold comprises the base plate 1 and the side plates 2, 3, 4, and 5, preferably of wood. The side plates 3 and 5 are clamped in position by means of the transverse bolts 6 provided 75 with suitable nuts, the plates 2 and 4 being held by the clamping action of the bolts and by reason of the engagement of their outer faces with the bolts as indicated in Fig. 2.

A lining of plaster board in the form of the sheets 7, 8, 9, 10, and 11 is provided upon the interior of the mold. The material used for this purpose is preferably commercial plaster board about one-quarter inch thick, although 80 the thickness of the plaster board and its composition may be varied to suit conditions. One form of plaster board which has been found to meet the requirements satisfactorily 85 is made in accordance with the following formula:

Wood fiber	2,500	pounds
Waste paper	500	"
Sulphite	150	"
Lime	500	"
Cement	2,000	"
Stucco	22,000	"

The sulphite of the formula is a paper pulp such as is formed in the production of 105 paper, wherein the materials are heated in a digester in connection with sulphuric acid. This material is not essential but makes the mass stick together better. The stucco of the formula is plaster of Paris and the 110

cement is ordinary Portland cement. This plaster board is one which is upon the market and is in the form of sheets which are relatively porous and much lighter and stronger than plaster of Paris and at the same time has a capacity for absorbing moisture to substantially the same extent as plaster of Paris.

The plaster board is preferably merely set in position inside the mold, although if desired it may be tacked in position, after which the clay is poured in the mold in the usual way and allowed to set. The setting of the clay requires from twenty-four to forty-eight hours, after which the plates 2, 3, 4, and 5 with the plaster board lining is removed, leaving the clay article upon the sheet 7 carried by the plate 1. The final drying operation requires several weeks, after which the block is ready for arching in the usual way.

After their removal the plaster board sheets are allowed to dry out and can be then used again. The plaster board is relatively strong and durable and may be used over and over again, so that the expense incident to the use of plaster is reduced to a minimum. If desired, metal plates may be used as the supporting structure, although wood is preferable and the strength and lightness of the material makes it possible to cast articles of large size such as the tuilles, pots, and floaters heretofore referred to. In the case of larger articles a thicker plaster board may be employed in order to give greater absorbing capacity, or several thicknesses of plaster board may be used. A number of different kinds of commercial plaster boards may be employed, although the one specified heretofore is preferred.

When it is desired to produce an article with a circular wall, such as a pot, the expedient illustrated in Fig. 3 may be employed in order to avoid the necessity of bending the plaster board. As here illus-

trated, the mold wall is made in the form of panels, the boards 12 constituting the supporting framework and the sheets 13 being of plaster board. This forms a supporting wall which is sufficiently near to circular form to meet requirements and which does not require any bending of the materials employed. The material may be readily adapted to a large number of different forms, it being a relatively simple matter to construct a mold of the desired shape out of wood and cut the plaster board sheets to form a lining. The cost of the materials employed is much less than in the case of solid plaster walls, and there is practically no breakage or cracking incident to handling, such as is the case with molds formed of solid plaster. The mold is also much lighter than is the case with solid plaster molds, so that the labor incident to handling is much less. Other advantages incident to the construction will be readily apparent to those skilled in the art.

What I claim is:

1. In combination in a mold for casting clay articles, walls comprising plates of relatively strong material having a facing of sheets of commercial plaster board.
2. In combination in a mold for casting clay articles, walls comprising plates of relatively strong material having on their faces sheets of plaster board, such board comprising a mixture of plaster-of-Paris and wood fibre.
3. In combination in a mold for casting clay articles, walls comprising knock-down plates each having upon its inner side a sheet of commercial plaster board made up of plaster-of-Paris and wood fibre.

In testimony whereof, I have hereunto subscribed my name this 5th day of August, 1920.

ROBERT W. WHITE.

Witness:

BROCCARD F. BRANDLESS.
